RADIATOR

Filed March 30, 1929

Inventor:
W. J. Kenney

By Wm. F. Freudenberg, *Attest.*

UNITED STATES PATENT OFFICE

WILLIAM J. KENNEY, OF CHICAGO, ILLINOIS

RADIATOR

Application filed March 30, 1929. Serial No. 351,447.

The present invention has for its object to produce a radiator for heating air that shall be light and of simple construction; that shall be efficient in operation, not only 5 in the sense of efficiently interchanging heat energy, but also in the sense of reducing the resistance to the free flow of air past the heating elements; and that shall produce a more effective distribution of the heat in a room or 10 space wherein the radiator is situated, than has heretofore been possible through the use of radiators alone.

In carrying out my invention I so construct the radiator that there will be air passages 15 extending up from the bottom of the same and out through the side; the passages being gradually curved so that the air flowing up through the same is not required to change its course abruptly. Furthermore, the passages become progressively enlarged, to compensate for the natural expansion of the air as 20 its temperature is rising during its passage through the radiator; thus avoiding a choking effect and reducing the resistance to a minimum. When such a radiator is placed in 25 a room, the heated air is not travelling in the vertical direction as it leaves the radiator, but it is moving approximately horizontally; thus producing a higher temperature in the zones occupied by the people in the room 30 than that in the case of an ordinary radiator. In other words, a highly desirable distribution of the heated air is secured without the use of fans or other means acting on the air after it leaves the radiator. A radiator of 35 this kind is particularly adapted for situations where it must be placed within a wall, since it will function precisely and deliver into the room the same amount of heated air, flowing at the same speed and in the same direction, as though the radiator were standing out in the room.

The various features of novelty whereby my invention is characterized will herein- 45 after be pointed out with particularity in the claims; but, for a full understanding of my invention and of its objects and advantages reference may be had to the following detailed description taken in connection 50 with the accompanying drawings, wherein:

Figures 1 and 2 are respectively a front and a side elevation of a radiator constructed in accordance with the present invention; Fig. 3 is a section on line 3—3 of Fig. 1, on a somewhat larger scale the fins being omitted; Fig. 4 is a front view, on a still larger scale, of a fragment of the radiator at one upper corner; Fig. 5 is a section on line 5—5 of Fig. 4; and Fig. 6 is a section taken approximately on line 6—6 of Fig. 5. 55 60

Referring to the drawings, 1 and 2 represent two hollow heads connected together by a series of comparatively thin hollow walls of which five, indicated at 3, 4, 5, 6 and 7, are shown. The hollow walls connect the interiors of the two heads together. If hot water, for example, is allowed to flow into the head 1 through a pipe 8, for example, and out from the head 2 through a pipe 9, it will pass from the head 1 to the head 2 through the several hollow walls. The hollow walls are arranged one in front of the other, corresponding ends terminating short of the plane of the bottoms of the heads if there are no legs or other means to support the device in such a manner that air may enter into the spaces between the lower ends of the walls. The hollow walls extend upwardly and forwardly, being progressively, preferably gradually, curved from one 70 end to the other. The curvatures are such that the walls divert gradually from each other as they rise and bend forwardly, thus causing each of the spaces bounded on two sides by two of such walls to increase gradually in cross-sectional area. Therefore, the spaces between the hollow walls being passages for the air that is being heated, the air entering the passages at the bottom of the radiator is free to expand naturally as 75 it rises and has its temperature increased, so that there will be no back pressure in the passages tending to choke back the flow of air. 80 85

The radiator being set in a room, for example, and hot water being supplied to the radiator in any usual or suitable manner, the air will move upwardly through the air passages and will be discharged in a heated condition in an almost horizontal direction; 90 95 100

the result being that the heated air moves laterally into the room and heats the lower and intermediate regions, instead of rising straight to the ceiling or roof from the 5 radiator.

10 The surfaces of the hollow walls, of themselves, will not interchange sufficient heat, and therefore I provide each air space with numerous heat interchanging fins whose combined superficial areas will be very great. In the arrangement shown, I have placed in each of the air passages a large number of thin parallel vanes each extending entirely across the passage and engaging at its edges 15 with the two corresponding hollow walls; the vanes preferably standing in vertical planes. Each vane is preferably provided with flanges 11 extending laterally therefrom at its two long edges, the flanges lying in intimate contact with the hollow walls and insuring that heat from the hollow walls will be carried into the vanes. The flanges on the vanes also serve as spacers to hold the vanes apart, thus greatly facilitating the 20 assembling of the vanes in one of the passages; the vanes being simply dropped into the passages while one of the headers is disconnected and, through their flanges, being self-spacing.

25 30 The parts of the radiator may be made of any suitable material as, for example, sheet copper, so that a large amount of air can be efficiently heated and distributed by a comparatively small and light radiator.

35 While I have illustrated and described with particularity only a single preferred form of my invention, I do not desire to be limited to the exact structural details thus illustrated and described; but intend to cover 40 all forms and arrangements which come within the definitions of my invention constituting the appended claims.

I claim:—

45 1. A radiator having long air passages extending through the same and increasing progressively from their inlet ends toward their outlet ends, a series of parallel longitudinal individual partitions extending through and fitting in each passage, and 50 flanges at the long edges of each partition lying flat against the adjacent bounding walls of the passage.

55 60 2. In a radiator, two separated hollow heads, comparatively thin hollow walls extending between the heads and connecting their interiors together, said walls rising from the bottom of the radiator and curving laterally to one of the sides, and the walls diverging from their lower ends toward the top to produce between them open-ended air passages increasing gradually in cross-sectional area from their lower to their upper ends.

65 3. A radiator comprising a series of long wide heat-emitting elements arranged one

70 behind the other and extending in smooth curves from the bottom of the radiator upwardly and to one side of the latter and producing a plurality of open-ended air passages, the curvature of each of said elements being less sharp than that of the elements in front of the same to cause said air passages to increase in cross sectional area from the lower ends upwardly.

75 4. A radiator comprising a series of long wide heat-emitting elements arranged one behind the other and extending in smooth curves from the bottom of the radiator upwardly and to one side of the latter and producing a plurality of open-ended air passages, the curvature of each of said elements 80 being less sharp than that of the elements in front of the same to cause said air passages to increase in cross sectional area from the lower ends upwardly, and partitions extending lengthwise through said passages in intimate contact with said heat-emitting elements.

85 5. A radiator comprising a series of long, wide, thin hollow walls arranged one behind the other and extending upwardly from the bottom of the radiator and forwardly in smooth curves of such a character that the open-ended air passages formed between said walls increase gradually in size toward their 90 upper ends, and means connected to said walls to cause them to be filled with a hot fluid.

95 6. A radiator comprising a series of long, wide, thin hollow walls arranged one behind the other and extending upwardly from the bottom of the radiator and forwardly in smooth curves of such a character that the open-ended air passages formed between said walls increase gradually in size toward their 100 upper ends, numerous partitions extending lengthwise through said passages in intimate contact with said walls, and means connected to said walls to cause them to be filled with a hot fluid.

105 110 In testimony whereof, I sign this specification.

WILLIAM J. KENNEY.
